US00D819262S

(12) **United States Design Patent** (10) **Patent No.:** **US D819,262 S**
(45) **Date of Patent:** **** May 29, 2018**

(54) **ELECTRONIC CIGARETTE**

(71) Applicant: **Shenzhen Hotom Technology Co., Ltd.**, Shenzhen (CN)

(72) Inventors: **Peng Lin**, Shenzhen (CN); **Yunjie Liu**, Shenzhen (CN)

(73) Assignee: **Shenzhen Hotom Technology Co., Ltd.**, Shenzhen (CN)

(**) Term: **15 Years**

(21) Appl. No.: **29/569,566**

(22) Filed: **Jun. 29, 2016**

(51) LOC (11) Cl. **27-01**

(52) U.S. Cl.

USPC **D27/101**

(58) **Field of Classification Search**

USPC D27/101, 100, 106, 108, 139, 141, 142, D27/163, 165, 169, 172, 174, 175, 183, D27/186–190, 193, 194, 195; D24/100, D24/110, 113; 131/270, 273, 274, 191, 131/330, 328, 329; D7/300, 300.1, 312, D7/313, 500, 509, 514, 515; D9/516, D9/545, 549, 551, 520, 544

CPC A24F 47/002; A24F 47/004; A24F 47/006; A24F 47/008; A61M 15/06

(57) **CLAIM**

The ornamental design for an electronic cigarette, as shown and described.

DESCRIPTION

FIG. 1 is a perspective view showing our design;
FIG. 2 is another perspective view showing our design;
FIG. 3 is a front view showing our design;
FIG. 4 is a back view showing our design;
FIG. 5 is an enlarged top view showing our design;
FIG. 6 is an enlarged bottom view showing our design;
FIG. 7 is a left view showing our design; and,
FIG. 8 is a right view showing our design.
The broken lines in the drawings depict a portion of the electronic cigarette that form no part of the claimed design.
